(57) **CLAIM**

We claim the ornamental design for the steering wheel, as shown and described.

DESCRIPTION

FIG. 1 is a front perspective view of a steering wheel showing our new design;

FIG. 2 is a top view thereof;

FIG. 3 is a left side view thereof;

FIG. 4 is a right side view thereof;

FIG. 5 is a front view thereof;

FIG. 6 is a rear view thereof; and,

FIG. 7 is a sectional view thereof taken along line 7 in FIG. 2. The broken lines shown in the drawings illustrate portions of the steering wheel that forms no part of claimed design.
